UNITED STATES PATENT OFFICE.

JOHN T. HAWKINS, OF TAUNTON, MASSACHUSETTS.

MEANS FOR SECURING FLEXIBLE PRINTING-PLATES.

SPECIFICATION forming part of Letters Patent No. 427,320, dated May 6, 1890.

Application filed May 16, 1889. Serial No. 310,956. (No model.)

To all whom it may concern:

Be it known that I, JOHN T. HAWKINS, of Taunton, in the county of Bristol and State of Massachusetts, have invented new and useful Means for Securing Flexible Printing-Plates to the Beds, Cylinders, and Turtles of Printing-Machines, which invention is fully set forth and illustrated in the following specification and accompanying drawings.

10 The object of this invention is to provide means for securing comparatively thin printing-plates upon either the flat beds or cylindrical surfaces of printing-machines, whether for relief-printing or by the lithographic method commonly known as "zincographic" printing.

The invention will first be described in detail, and then particularly set forth in the claims.

20 In the accompanying drawings, Figure 1 illustrates a broken vertical section of a flat bed, showing two modifications of the plate-straining apparatus; and Fig. 2, a partial plan showing only one of the modifications 25 of the straining apparatus. Fig. 3 shows a vertical section of a cylindrically-surfaced turtle with printing-plate attached. Fig. 4 shows a transverse section of a printing-cylinder on which a single thin printing-plate 30 is strained into contact therewith by its two opposite ends, and Fig. 5 shows a partial plan of the same parts. Fig. 6 shows a transverse section of a cylinder carrying two printing-plates having each a straining apparatus 35 supplied to one end only, and Fig. 7 is a partial plan of the same parts. Fig. 8 illustrates a portion of a detached plate in two views, enlarged, showing the method of preparation of the plate. Fig. 9 shows a sectional view 40 of grooved blocks or bars, enlarged, herein-after particularly described.

In said figures the several parts are indicated by reference-numbers, as follows:

The number 1 indicates the bed, turtle, or cylinder, and 2 the thin printing-plate held in contact therewith.

In Figs. 1, 2, 3, 6, and 7 a grooved block or bar 3 is attached to one edge of the printing-surface of the bed, turtle, or cylinder, the 50 groove 7 in which receives the tongues 8, formed along one edge of the printing-plate, and for the opposite edge of the printing-

plate a similar grooved block or bar 4 is attached to the free end of a straining-plate 5. The straining-plate 5 may be jointed or fulcrumed to the bed, turtle, or cylinder, as shown near the central part of Fig. 1, or it may be formed as a thin elastic plate 5, secured at its fixed end to the bed, turtle, or cylinder by screws, as 6, or other suitable means, as shown at the right of Fig. 1 and in the other figures. The grooved blocks or bars 3 and 4 have the longitudinal groove 7, Fig. 9, cut in them at an acute angle with the surface upon which the plate rests, the groove being a little wider than the thickness of the plate to be held, so that the tongues 8 may enter it freely, and the plate 2 has punched along its two opposite edges at any desired interval a line of tongues 8, 70 which are bent in the act of punching to make an angle with the plate corresponding with that of the groove 7 in the blocks 3 and 4.

The tongues 8 of the printing-plate may be 75 of any suitable form, so that they may be bent upon a right line parallel with the edge of the plate, and not punched out on that line. In Fig. 8 at the left they are shown semicircular, as preferably made, and at the 80 right as square in form, though octagonal or any desired form may be given to the free punched - out parts of the tongues. The straining-screws 9 are tapped in the grooved blocks or bars 4, impinging against the metal 85 of the bed, turtle, or cylinder, and the elastic character of the thin plate 5, when so constructed, or its fulcrum-pivot, when pivoted, as shown in part of Fig. 1, permits of the printing-plate 2 being strained at will by 90 means of the screws 9.

With some very thin printing-plates it is to be understood that the elastic - spring straining-plate 5, when used, may be adjusted to have an outward tension, which may be 95 sufficient for the straining of such very thin printing-plates without resorting to the use of the straining-screws 9; but when the straining-plate 5 is fulcrumed or jointed to the bed, turtle, or cylinder the straining-screws 9 must 100 be used.

Having thus fully described my said improvements as of my invention, I claim—

1. In an apparatus for securing thin print-

ing-plates to the beds, turtles, or cylinders of printing-machines, the combination of a printing-plate having tongues, as 8, partially punched out within and at suitable distance 5 from the edge of the same, so as to stand leading inward from said edge at an acute angle with said plate, grooved bars, as 4, carrying therein grooves, as 7, formed at a suitable angle for the reception of said tongues, secured 10 to the free ends of mobile straining-plates, as 5, and straining-screws, as 9, substantially as and for the purposes set forth.

2. In an apparatus for securing thin printing-plates to the beds, turtles, or cylinders of printing-machines, the combination of a printing-plate having a series of tongues, as 8, partially punched out within and at suitable distance 15 from two opposite edges of said print-

ing-plate, so as to stand leading inward from said edges at an acute angle with said plate, 20 a grooved bar, as 3, having a groove, as 7, formed in it at a suitable angle for the reception of one series of said tongues, and secured to one edge of the printing-surface of said bed, turtle, or cylinder, and inobile straining-plates, as 5, to the free ends of which grooved bars, as 4, are secured by suitable straining-screws, as 9, whereby said printing-plate is 25 securely held and strained into close contact with said bed, turtle, or cylinder, substantially as and for the purposes set forth.

JOHN T. HAWKINS.
